UNITED STATES PATENT OFFICE.

JOHAN WALDEMAR LINDBERG, OF STOCKHOLM, SWEDEN.

LOCK.

1,329,418.

Specification of Letters Patent.

Patented Feb. 3, 1920.

Application filed April 22, 1918. Serial No. 230,071.

To all whom it may concern:

Be it known that I, JOHAN WALDEMAR LINDBERG, a subject of the King of Sweden, residing at Stockholm, in the Kingdom of Sweden, have invented a new and useful Improvement in Locks, of which the following is a specification.

This invention relates to an improvement in locks having for its purpose to substitute keys punched or pressed out of sheet metal for the forged or drop-forged keys heretofore used. In this manner the cost of the keys will be materially reduced and it will also be possible when making the key simultaneously to punch or press out the various steps or teeth of the bit, that is to say the face of the key, if desired.

The present invention is broadly characterized by this, that the key-hole in the top plate or the bottom plate of the lock consists of a semi-circular or nearly semi-circular slot and a slot for the key-bit extending preferably radially from the first-named slot. The other plate of the lock may preferably be provided with a slot or a depression corresponding or nearly corresponding to the semi-circular slot in the first-named plate. The key of the lock is broadly characterized by this that its "pipe" or shank has about semi-circular cross section and is provided with a bit extending preferably radially from the same.

In the accompanying drawing there are shown by way of example two embodiments of the invention. Figure 1 shows a perspective view of a lock with its key-guard and key, according to the first embodiment. Fig. 2 shows a side view of the key and Fig. 3 shows a section of the key-shaft on the line III—III in Fig. 2. Fig. 4 shows the key-guard, Fig. 5 shows the top plate of the lock, and Fig. 6 shows the bottom plate of the lock, a key-support secured to the same being shown in section. Fig. 7 shows a section of the key according to the other embodiment, Fig. 8 shows the corresponding key-guard, Fig. 9 the top plate of the lock, and Fig. 10 the bottom plate of the lock.

The key 1 may be punched or pressed out of a metal sheet of suitable thickness, and it is provided with a semi-cylindrical groove 2 pressed simultaneously or afterward, so that the pipe or the shank 3 shows the form of approximately half a cylindrical shell.

From this shell the bit 4 extends, the face 55 of which may be pressed out simultaneously with the key, if desired. The key-hole in the top plate 5 of the lock has a shape corresponding to the cross section of the key and consists of an about semi-circular slot 6 60 for the pipe or the shank of the key from which slot 6 a slot 7 for the bit extends in about radial direction.

In order to make the key capable of being turned when inserted in the key-hole in the top plate of the lock the key is provided with an arc shaped slot 8 which subtends an angle equal to or somewhat greater than the angle through which the key is to be turned for opening the lock. The bottom plate 9 of the lock is preferably provided with a circular slot 10 or a depression which serves for guiding the end of the key. This slot 10 need of course not extend over a greater angle than the sum of the angle 75 taken up by the key-shank and the angle which the key is to be turned.

The key-guard 11 is provided with a key-hole corresponding to the hole in the top plate of the lock, but the semi-circular portion of this key-hole is extended in the direction of turning of the key equally or a little more than the angle of turning of the key so as to enable the key to be turned in the slot in the key-guard without the key 85 having to be provided with an extra slot.

Between the top plate and the bottom plate of the lock there is preferably secured a member or a support 20 which borders the edges of the slots 6 and 7 in the top plate and the slot 10 in the bottom plate. The support 20 thus extends parallelly with the direction of the key-hole, that is to say in ordinary cases it extends at right angles to the top plate and the bottom plate of the lock. When the key is introduced in the key-hole it gains support against the member 20 so that it will be prevented from moving in lateral directions. It will be understood that the support 20 is only provided along the edges of the slots 6, 7 and 10 which do not lie within the angle of turning of the key, as the support would otherwise prevent the key-bit from being turned in the lock. This support 20 may of course be secured to both the top plate and the bottom plate of the lock, or to either the top plate or the bottom plate in which

latter case it need not extend over the whole distance between the top plate and the bottom plate.

The embodiment shown in Figs. 7-10 is distinguished from the embodiment above described by the semi-cylindrical depression being made on the other side of the key, which requires the slots in the key-guard as well as in the top and the bottom plates of the lock to be correspondingly shaped. The slot 12 which permits the key to be turned in the key-hole in the top plate of the lock is of course provided in the edge of the key-shank opposite the key-bit. The slot 13 in the key-guard 15 and the slot 14 in the bottom plate 16 of the lock are preferably also in this case extended in the direction of turning of the key relatively to the slot 17 in the top plate 18 of the lock, as will be understood from the drawing.

It will be understood that the invention is not limited to the embodiments above described and illustrated in the drawing, but that alterations may be made within the scope of the invention as set forth in the claims. The key need for instance not be provided with a slot 8, but the slot 6 in the top plate of the lock may be correspondingly extended. On the other hand, instead of making the slot 10 extended, the key may be provided with a corresponding slot or recess at its end. The key-bit and the slot corresponding to the same need of course not extend radially from the key-shank and need not be straight, but may be bent to a suitable profile.

I claim:

1. In a lock the combination of a top plate provided with a key-hole consisting of an approximately semi-circular slot and a slot extending about radially from the first-

named slot, and a bottom plate provided with a slot corresponding to the semi-circular slot in the top plate.

2. In a lock the combination of a top plate 45 provided with a key-hole consisting of an approximately semi-circular slot and a slot extending about radially from the first-named slot, and a support extending from the edges of the said key-hole parallelly with 50 the direction of the key-hole.

3. In a lock the combination of a top plate provided with a key-hole consisting of an approximately semi-circular slot and a slot 55 extending about radially from the first-named slot, a bottom plate provided with a slot corresponding to the semi-circular slot in the top plate, and supports between the top plate and the bottom plate extending from the edges of the key-hole in the top 60 plate and adjacent to the key position but outside of the same to prevent interference when the key is turned.

4. The combination with a lock provided with a key-hole consisting of an approximately 65 semi-circular slot and a slot extending about radially from the first-named slot, of a key provided with a shank of about semi-circular cross section and a key-bit extending about radially from said shank. 70

5. The combination with a lock provided with a key-hole consisting of an approximately 75 semi-circular slot and a slot extending about radially from the first-named slot, of a key provided with a shank of about semi-circular cross section and a key-bit extending about radially from said shank and with a slot in the shank, said slot having an angular extension equal to the angle of turning of the key in the lock.

JOHAN WALDEMAR LINDBERG.
